ABSTRACT OF THE DISCLOSURE

A thin, hollow shell for a piling is tensioned and stressed a predetermined amount over a driving mandrel to facilitate driving the shell without excessive damage thereto.

Background of the invention

This invention relates to a method and apparatus for driving thin pile shells and more particularly to a method and apparatus for pretensioning a thin-walled pile shell so that it may be driven without causing excessive damage thereto.

In the placement of concrete and similar pilings in an earth formation it is often necessary to place thin, hollow shells in the formation prior to formation of the body of the pile. Such thin-walled shells are necessary, especially in areas where the earth formation is soft or loose and likely to cave into the borehole. It is desirable to use as thin a pile shell as possible because of the great savings in material where a great many piles are used. The use of thin-walled pile shells, however, has been quite limited in the past because of the lack of an effective method of inserting such shells into the soil formation without excessive damage thereto. Thin-walled pile shells have generally been driven by means of either a plug which engages the lower end of the pile and is driven downward into the formation, pulling the pile shell with it, or by means of an internal mandrel which also engages the lower end of the pile and is driven downward into the formation, pulling the pile shell with it. With the use of either the plug or the mandrel the driving force is applied primarily to the lower end of the pile shell while the resistance force applied by the soil is generally applied along the entire length of the pile shell. The movement of the shell is greatest at the bottom and diminishes toward the top. Under such conditions the pile shell is deformed or otherwise greatly damaged by being stretched or torn apart.

It is therefore an object of the present invention to provide a method and apparatus for driving thinner-walled pile shells than has heretofore been possible.

In accordance with the present invention, an elongated driving mandrel having a pretensioning clamp means near its upper end is inserted in a thin-walled pile shell and the shell stretched thereover.

Brief description of the drawing

A greater understanding of the present invention may be obtained from a reading of the following description in conjunction with the accompanying drawings in which:

FIGURE 1 is an elevational view illustrating the general arrangement of a drive mandrel in position to be inserted into the central bore of a telescoped, thin-walled pile shell.

FIGURE 2 is an elevational view partially in section illustrating the arrangement of the driving mandrel lowered into the shell assembly with the shell assembly extending over the drive mandrel.

FIGURE 3 is an elevational view partially in section illustrating the arrangement in the shell assembly in driving condition with the pile shell stretched over the drive mandrel.

2

FIGURE 4 is an elevational view partially in section illustrating the clamping and stretching apparatus of the present invention.

FIGURE 5 is an elevational view partially in section illustrating the gripping apparatus of the present invention in engagement with the wall of a thin pile shell.

FIGURE 6 is an elevational view partially in section showing the gripping and stretching apparatus of the present invention in gripping engagement with the end wall of the pile shell and extended to its uppermost or stretched position.

FIGURE 7 is a side elevation partially in section illustrating the lower end of a thin-walled corrugated pile shell prepared for driving by the apparatus of the present invention.

Description of preferred embodiments

Taking a look now at FIGURE 1, there is shown a driving mandrel 11 which is stepped in sections 11a, 11b and 11c which are adapted to engage and drive a telescoping pile such as that shown at 12. A pretensioning clamp 13 is suitably connected or mounted on the upper end of the driving mandrel. The driving mandrel 11, as illustrated, is a step-tapered cylindrical tubular member having a plurality of abutting or drive shoulders 14 and 15. The telescoping pile 12 which the illustrated mandrel is adapted to drive is a telescoping pile made up of a plurality of sections 12a, 12b and 12c which are connected together by means of flanges 16 and 17, as more fully detailed in FIGURES 2 and 3, or other suitable means. The upper end of section 12a and 12b comprises an outwardly-directed annular flange member 16 and 17 on the upper end thereof. Each pile section 12b and 12c comprises an inwardly-directed annular flange member 16a, 17a on the lower end thereof to engage the outwardly-directed flange of the next adjacent section of shell. These flange members 16, 16a and 17, and 17a are adapted to abut or engage as shown in FIGURES 2 and 3 so that tension applied to the next upper section of shell will be transmitted to the engaged lower section of shell. The abutting or drive shoulders 14 and 15 are adapted to engage the corresponding flange shoulder 17b and 16b, respectively, of each shell section.

Each step section 11a, 11b or 11c of the drive mandrel is longer by a predetermined amount than each of the pile sections 12a, 12b or 12c, or at least its corresponding section of the telescoping shell that is to be driven. This predetermined excessive length of each step section of the driving mandrel over its corresponding section of telescoping shell insures that each section of the shell is stretched and therefore tensioned as the shoulders 17b and 16b of the sections come into engagement with the corresponding drive shoulder 14 and 15 of the driving mandrel. Suitable means such as a plate, plug or ring 18 is provided at the lower end of the lowermost section of the pile shell, as shown in FIGURE 3, for engagement by the lower end of section 11a of the drive mandrel 11. The drive mandrel and the pretensioned pile shell, as shown in FIGURE 3, is driven to the desired depth in an earth formation by any suitable means such as by a pile-driving hammer or by a sonic oscillator 19. A pile driver of the hammer type is well known and needs no discussion here. A driver of the sonic oscillator type suitable for the present invention may be of a type generally disclosed in U.S. Patent No. 2,975,846. Such sonic oscillators operate by establishing longitudinal elastic vibrations in the pile shell and the mandrel which results in a penetration of the shell and the mandrel into the earth formation.

The clamping and pretensioning apparatus of the present invention is more clearly illustrated in FIGURES 4-6. The clamping and pretensioning apparatus comprises a cylindrical central body members 20 having a central

throughbore 21 and an annular skirt or flange member 22. The annular body member 23 is connected, as by threads 20a, to the lower end of the central body member 20 on the outside thereof and has a skirt portion 24 which extends upward and concentrically along the central body member 20 in spaced relation thereto to form an annular wedge containing pressure chamber 25. An annular clamp wedge actuating piston 26 is mounted in sealed relation in pressure chamber 25 and extends upward along the outer cylindrical surface of the central body member 20. The actuating piston 26 has an outwardly sloping cam surface 27 around which is circumferentially spaced a plurality of clamp wedges 28, each having a gripping surface 28a formed with teeth or serrations to enhance gripping. The clamp wedges 28 may be held in spaced relation around and in engagement with the camming surface 27 by means of a plurality of grooves which may be preferably of a dovetail configuration. A downwardly-extending annular clamp skirt 29 is connected by suitable means, such as by studs or bolts 30, to an annular piston member 31 which is reciprocably mounted in sealed relationship in annular chamber 32. The annular skirt 29 has an annular internal gripping surface 29a which is preferably formed with teeth or other forms of serrations to gripping of a pile shell. An annular pressure release or wedge release pressure chamber 33 is formed between clamp wedge actuating piston 26 and central body member 20. Conduit means 34 supplies hydraulic fluid to the annular pressure chamber 33. Fluid is supplied to pressure chamber 25 for driving annular piston 26 upward by means of pressure fluid from conduit 35. The annular piston 31 is moved downward by means of fluid under pressure in pressure chamber 32 which is supplied by conduit member 36. An adjustment collar 37 is threadably mounted by means of threads 29a on the outer surface of clamp skirt 29 for adjustment thereon to adjust the pretensioning that is to be applied to the pile shell member. A pretensioning adjustment scale 38 indicates the amount of pretensioning. A lock screw 39 locks the adjustment collar into place after adjustment to prevent accidental movement thereof during operation of the device.

The lower limit of travel of the stretching or tensioning assembly of the present apparatus is determined by stop shoulder or the engagement of stop shoulder 37a with stop shoulder 22a. The distance of shoulder 37a above shoulder 31a on piston 31 is adjustable by rotating collar 37 and determines the distance of travel of the pretensioning piston assembly and thus the amount of tensioning that may be applied to a pile shell. The upper limit of travel of the tensioning piston assembly is determined by the engagement of shoulder 31a with the lower end of skirt member 22.

In operation or in carrying out the present invention, a driving mandrel is selected which has the proper dimensions with respect to the dimensions of the thin-walled pile shell which it is desired to drive. As illustrated (FIGURE 1) with respect to the present invention, the driving mandrel 11 is lowered into the center of a nest of telescoped pile shells 12a, 12b and 12c with the lower end of the driving mandrel engaging the lower end of the lower shell section 11a (FIGURE 3) by means of a plate 18, or other engaging means such as, for example, a flange, would be suitable. As shown in the illustration of the telescoped shell, the telescoped pile shell is pulled up over the mandrel (FIGURE 2) such as by aid of a hoist line 40 and upward for engagement by the clamp and tensioning means. The clamping assembly 26-28-29-30-31 is moved downward to a predetermined lowermost position by increasing the fluid pressure in chamber 32 and lowering the pressure in chamber 25. This predetermined position is selected by means of collar 37, and is determined by the amount of stretch of the pile shell needed to obtain the desired tension. The upper end of the pile shell is inserted between 75

the clamping wedges 28 and clamping skirt 29, as shown in FIGURE 4. The clamp wedge actuating piston 26 is then actuated by the injection of hydraulic fluid into pressure chamber 25 which moves piston 26 upward, camming clamp wedges 28 outward into engagement with the shell member 12 as shown in FIGURE 5, clamping the shell member between the wedge members 28 and the clamp skirt 29. Continued application of hydraulic pressure into pressure chamber 25 continues to move the piston assembly 26 and the clamping assembly 28-29-30-31 upward carrying therewith the upper end of the shell member 12. When the pile shell is first brought into position for clamping between the jaws of the clamping assembly, the pile shell will appear as shown in FIGURE 2 with the abutting shoulder 16a standing away from the driving shoulder 15 of the mandrel. As continued pressure is applied into the pressure chamber 25, the clamping and the tensioning assembly moves upward pulling each successive pile shell abutting or drive shoulder into engagement with the corresponding abutting or drive shoulder on the driving mandrel, as shown in FIGURE 3. With the shell in its stretched or tensioned position as shown in FIGURE 3, the pile shell and mandrel are raised to be driven to the desired depth in an earth formation. After the shell has been driven to the desired depth in the earth formation, the upward pull on the pile shell is then released or relaxes and the clamping engagement released by lowering the pressure in chamber 25 and increasing pressure in chamber 33, thus permitting the drive mandrel to be removed from the center of the pile shell as a slurry of solidifiable material such as cement or concrete is pumped downward through the hollow bore of the mandrel, thus filling the shell as the mandrel is withdrawn.

Although a tapered telescoping pile has been illustrated in conjunction with the explanation of the practice of the present invention, it is to be understood that the present invention is applicable to the driving of long non-telescoping tapered piles, single diameter pile shells, and other similar structures as would be apparent from the foregoing illustration. Also, it is apparent that corrugated pile shells may be driven in accordance with the practice of the present invention, as illustrated in FIGURE 7. As shown in FIGURE 7, the corrugated pile shell 41 is provided with abutting means in the lower end thereof such as, for example, plug member 42, which is connected in any suitable manner such as by welding into the end of the pile shell member. The plug 42 is adapted to be engaged by the driving mandrel 11 as the pile shell is stretched over the mandrel and driven into the earth formation. A driving cap 43 may be provided for the lower end of the pile shell to facilitate penetration thereof.

While the invention has been described with respect to a specific embodiment, it is to be understood that many modifications thereof may be made without departing from the scope of the invention which is to be limited only by the scope of the appended claims.

I claim as my invention:

1. An apparatus for pretensioning thin pile shells to improve the driving thereof, said apparatus comprising: an elongated driving mandrel adapted to extend into a pile shell; shell abutting means carried by the lowermost end of said driving mandrel for drivingly engaging said pile shell at the lower end thereof for applying a bias thereto in an axial direction; tension-applying means operatively carried at the top of said driving mandrel for applying axial bias to said pile shell to elastically elongate said shell a predetermined amount to thereby pretension said shell; and clamping means operatively carried by said tension-applying means for operatively connecting said tension-applying means to the upper end of said pile shell.

2. The apparatus of claim 1 wherein:
said tensioning means comprises prime mover means.
3. The apparatus of claim 1 wherein:
said clamping means comprises a clamp operatively
actuated by said prime mover means for gripping the
upper end of said pile shell.
4. The apparatus of claim 1 wherein:
said driving mandrel comprises an elongated step-
tapered member comprising a plurality of abutting
shoulders.
5. The apparatus of claim 2 wherein:
said prime mover means comprises body means;
an annular chamber formed in said body means;
annular piston reciprocably mounted in said chamber;
and
cam means formed on said piston for moving said
clamping means into gripping engagement with said
pile shell.
6. The apparatus of claim 5 comprising:
adjustable stop means to adjust the limit of travel of 20
said piston.
7. The apparatus of claim 5 comprising:
a pressure chamber formed above said piston for re-
ceiving pressurized fluid for moving said piston
downward; and
a pressure chamber formed below said piston for re-
ceiving pressurized fluid for moving said piston
upward.
8. In a method of driving thin-walled piles the steps
of:

- selecting a hollow thin-walled pile adapted for engage-
ment with a driving mandrel;
selecting a driving mandrel having a diameter that is
slightly less than the internal diameter of said pile
and said pile having engaging means at its lower
end for engagement with said mandrel engaging
means;
inserting said driving mandrel in the bore of said pile
and into engagement with the interior wall adjacent
the lower end thereof;
engaging the upper end of said pile with tension-apply-
ing means;
applying tension to said pile to at least partially elasti-
cally elongate and thereby tension said pile over
substantially its entire length; and
driving said mandrel and said tensioned pile to a
predetermined depth in an earth formation.
